UNITED STATES PATENT OFFICE.

HENRY E. BULLOCK, OF CHICAGO, ILLINOIS.

COTTON-PICKING MACHINE.

No. 877,754.

Specification of Letters Patent.

Patented Jan. 28, 1908.

Application filed February 21, 1907. Serial No. 358,554.

To all whom it may concern:

Be it known that I, HENRY E. BULLOCK, subject of the King of Great Britain, residing at Chicago, in the county of Cook and State 5 of Illinois, have invented a certain new and useful Improvement in Cotton-Picking Machines, of which the following is a full, clear, concise, and exact description, reference being had to the accompanying drawings, forming 10 a part of this specification.

My invention relates to cotton picking machines, and has reference to the picking fingers thereof and also to the picker column construction.

15 As is well known, cotton picking machines include picker columns, each having a support for the bearings of picking fingers, an operating shaft journaled in the ends of the picker column, gear wheels provided upon 20 said shaft, and picking fingers carried by the bearings and projecting inwardly at their bases into proximity with the gear wheels and carrying gear wheels at their bases which mesh with the aforesaid gear wheels. Hitherto, the picking fingers have been formed of 25 substantially uniform diameter at the base portions thereof, where said fingers are liable to considerable wear.

In accordance with one object of my invention, I preferably thicken the base portions of the fingers, each finger desirably carrying two separated annular enlargements which are adapted to be borne by the finger bearing, the said finger enlargements 35 and the bearing supporting the same forming, with the portion of the finger between its enlargements, a pocket into which lubricating oil or other material may be received. This pocket is preferably annular. In order 40 that the life of the finger may be increased, I desirably make the said enlargement or enlargements of each finger removable, so that when they become materially worn, they may be replaced, whereby the original finger 45 may remain intact, inasmuch as its said enlargements, when made separable, will alone be subject to wear. Where it is desired to make these enlargements separable and at the same time provide two enlargements upon each finger, separated as hitherto stated, the said enlargements upon each finger may be made either in two distinct and separated sleeves or may be provided by one

sleeve having a groove (preferably annular) at an intermediate portion. 55

Another feature of my invention resides in providing bosses to constitute the bearings for the fingers, which bosses, in accordance with this feature of my invention, are enlarged in directions coincident with the 60 planes of movement of the fingers so as to afford sufficient metal in which oil passages may be formed to conduct oil from the interior of the picker column (which preferably has oil carrying capacity) to the finger bear- 65 ings.

I will describe my invention more fully by reference to the accompanying drawing, showing the preferred embodiments thereof, in which— 70

Figure 1 is a view in elevation showing so much of a picker column as is essential to an understanding of my invention, part of the structure being broken away for purpose of illustration. Fig. 2 is an enlarged sectional 75 view on line 2 2 of Fig. 1. Fig. 3 is a view of a part of a picker column showing a picking finger therein, being a modification of the structure illustrated in Figs. 1 and 2.

Like parts are indicated by similar characters of reference throughout the different figures. 80

The column support is desirably formed in two sections *a b*, the section *a* being provided with two bearings *c c* for the shaft *d*, to 85 which shaft motion may be imparted in any suitable and well-known way. The portion *a* of the support is desirably made semi-cylindrical at the rear and is provided with two parallel continuations of said semi-cylindrical portion, which parallel continuations terminate in marginal enlargements *e e*. The operating shaft *d* is provided with bevel gear wheels *f*, there being one such wheel to operate each cotton picking finger. 95 The support section *b* is preferably in the form of a plate that is fastened in position by means of screws *g* passing through the plate into the aforesaid marginal enlargements. This plate is provided with as many 100 bosses *h* as there are cotton picking fingers *i*, each boss *h* being sufficiently removed from the gear wheel *f* associated therewith to permit of suitable gearing connection. Said bosses are desirably formed or cast as integral parts of the plate *b* and have webs *k* 105

intervening between the same for strengthening purposes, said webs *k* being also desirably formed in the same casting. The picking fingers project through the bores in the 5 bosses, and each finger carries a wheel *l* on its inner end, that meshes with the corresponding wheel *f*, it being, of course, understood that the wheels *l* are fixed to the fingers *i* and that the wheels *f* are fixed to the shaft 10 *d*. The wheels are within the gear casing formed by the elements *a b*.

Each boss has its bearings desirably formed of substantially uniform diameter throughout, exceptat its middle portion *h*¹, 15 where, if desired, it may be slightly enlarged annularly for a purpose to be stated.

Each finger is preferably enlarged at its base so as to increase its wearing qualities, this enlargement, in the form of the invention shown in Figs. 1 and 2, comprising a 20 sleeve *m* separately formed from the finger and having a tight fit thereon. If desired, means may be supplied for preventing this sleeve from moving longitudinally of the 25 finger. I have, for the purpose, employed projections *n* that extend inwardly and project slightly into the material of the finger for the purpose stated, this fastening means being also indicated in the structure shown 30 in Fig. 3. When the bearing sleeve becomes worn, it may be removed and replaced by another.

Where the fingers are to be copiously supplied with oil for lubricating purposes, an 35 annular chamber, or a chamber of other suitable shape, may be provided at *h*¹, which chamber may have communication with the interior of the picker column through the channel *o*, from which the lubricating oil may 40 be fed into the chamber *h*¹. In order that this chamber may be of sufficient size, the portion of the sleeve *m* may be of reduced diameter where said chamber is located and the portion of the bore of the boss *h* may be 45 enlarged, so that oil, or other material that is to be fed to the fingers for any selected purpose, may have a sufficiently large holding chamber.

I preferably make the channel *o* of a large 50 size to constitute the same a reservoir, communication being had between said reservoir and the interior of the picker column by way of the duct portion *o*¹. Two duct portions *o*² *o*³ that converge toward the chamber *h*¹ 55 are provided for affording communication between the reservoir *o* and the chamber *h*¹, these duct portions being displaced longitudinally of the finger. By thus converging the channel portions *o*² *o*³, it will be seen that 60 if the finger is pointing downwardly, oil readily finds passage through the channel portion *o*², whereas if the finger is pointing upwardly, oil readily finds passage through the channel portion *o*³. The duct portions

*o o*¹ *o*² *o*³ are formed in an enlargement by the 65 boss *h*, which enlargement is directd in the plane of movement of the finger, where sufficient room is afforded. A cotton picking machine having its fingers thus equipped is provided with reservoirs individual to the 70 picking fingers thereof, as will be apparent.

In the construction shown in Fig. 3, the characteristics are generally similar to the characteristics shown in Figs. 1 and 2, with the exception that the portions of the sleeve 75 between which the oil-receiving chamber is to be formed, are totally separate and are separately disposable upon the fingers and separately removable therefrom. In this construction, the bore of the boss does not 80 necessarily need to be enlarged at *h*¹ where the oil chamber is to be located. While the removable sleeves are preferably of greater diameter than the balance of the finger, I do not wish to be limited to this construction. 85

While I have herein shown and particularly described preferred embodiments of my invention, I do not wish to be limited to the precise constructions herein shown, as changes may be made without departing 90 from the spirit of the invention, but,

Having thus described my invention, I claim as new and desire to secure by Letters-Patent the following:

1. A cotton picking machine including 95 picker columns each adapted to act as a main fluid reservoir, picking fingers, each provided with a displaceable enlargement in the form of a sleeve having portions between which a fluid-receiving groove or space in- 100 tervenes, and bearings engaging the enlargements of the picking fingers and located upon the exterior of the picker columns and carried thereby, each having a fluid-contain- 105 ing space in fluid conductive connection 110 with the picking finger it supports, there being a duct in the bearing intervening between this space and the main oil reser- 115 voir afforded by the associate picker column.

2. A cotton picking machine including 110 picker columns each adapted to act as a main fluid reservoir, picking fingers each provided with a displaceable enlargement in the form of a sleeve, and bearings engaging the enlargements of the picking fingers and 115 located upon the exterior of the picker columns and carried thereby, each having a fluid-containing space in fluid conductive connection with the picking finger it supports, there being a duct in the bearing 120 intervening between this space and the main oil reservoir afforded by the associate picker column.

3. A cotton picking machine including 125 picker columns each adapted to act as a main fluid reservoir, picking fingers, and picking finger bearings upon the exterior of the picker columns and carried thereby, each

having a fluid-containing space in fluid conductive connection with the picking finger it supports, there being ducts in the bearings intervening between these spaces and the 5 main oil reservoir afforded by the associate picker column.

In witness whereof, I hereunto subscribe

my name this 16th day of February A. D., 1907.

HENRY E. BULLOCK.
